UNITED STATES PATENT OFFICE.

MOSES G. FARMER, OF NEWPORT, RHODE ISLAND, ASSIGNOR TO THE UNITED STATES ELECTRIC LIGHTING COMPANY, OF NEW YORK, N. Y.

ELECTRIC LIGHTING APPARATUS.

SPECIFICATION forming part of Letters Patent No. 252,748, dated January 24, 1882.

Application filed January 19, 1880.

To all whom it may concern:

Be it known that I, MOSES G. FARMER, a citizen of the United States, residing at Newport, in the county of Newport and State of Rhode Island, have invented a new and Improved Electric Lighting Apparatus, as well as new and improved apparatus thereto pertaining, of which improvements the following is a specification.

10 My invention relates more particularly to a method of and apparatus for producing light by causing a current of electricity to traverse one or more sections of a conductor, which sections are composed of some suitable conducting material refractory to heat, having a considerably higher resistance per unit of length than the remainder of the circuit, by means of which resistance a portion of the electricity which traverses the circuit is converted into 20 heat, which, when of sufficient intensity, produces light.

The object of this invention is automatically to regulate the strength of current passing through a circuit in which electric lights are 25 included, so as to secure uniformity of illumination and avoid the liability of fusing the light-giving portions of the lamps.

The subject-matter claimed is hereinafter specifically designated.

30 Referring to the accompanying drawings, Figure 1 represents a plan or top view of the apparatus. Figs. 2 and 3 are elevations showing two opposite sides thereof. Fig. 4 is an end elevation of the same. Fig. 5 is a plan view of the apparatus with the top plate removed so as to exhibit the mechanism beneath, and Fig. 6 is a vertical longitudinal section of the same. Fig. 7 is a detached view, in elevation, of the electric cut-off apparatus. Fig. 8 35 is a detached view, in elevation, of one of the lamps, showing the details of its construction.

The frame of the apparatus consists of a base or bottom plate, B², to which are attached four upright standards, A' A² A³ A⁴, which serve 40 to support a top plate, B¹.

In the drawings, Figs. 1, 2, and 3, I have shown three lamps, L¹, L², L³, placed in three separate branches of one electric circuit, so arranged that the current divides itself be-

tween them inversely in proportion to their respective resistances. I will first describe the construction and mode of operation of these lamps, and afterward describe the mechanism which I prefer to make use of for automatically regulating the strength of the electric current passing through the lamps.

If a bar, wire, or strip of platinum, iridium, or other similar metal refractory to heat—that is, fusible only at a very high temperature—be made incandescent by the passage of an electric current through it, a mild and pleasant light is emitted, much less concentrated and glaring than the light obtained from the voltaic arc between carbon pencils, and of much more uniform character, provided the electric current is maintained at a uniform strength. Platinum affords a light equivalent to about one hundred candles per square inch of incandescent surface when within 220° of its temperature of fusion, while iridium, from its higher 50 melting-point, produces a still greater proportionate amount of light. In accordance with this principle, in constructing my lamp I make use of a bar or strip, w, of one of the herein-before-mentioned metals, preferably a flat strip, 55 as shown in Figs. 2 and 8, the thickness of which is about one-tenth less of its greatest breadth. This is affixed in an upright position between two metallic standards, P³ P⁴, in the manner best seen in Fig. 8, (which is a side elevation 60 of the lamp L', shown in the plan view, Fig. 1,) by means of suitable clamps, P' P². These standards are secured to a base of any suitable non-conducting material by means of screws f, f², or otherwise. A lever-switch, S³, provided with an insulating knob or handle, serves to close or open the branch of the circuit passing through the lamp when it is desired to turn the light on or off.

The lamp L³ (see Fig. 1) is provided with a 65 similar switch, S⁵. I sometimes prefer to use a different arrangement, known as the "peg-switch," (an example of which is seen at S⁴ in Fig. 1,) in which the circuit is completed by inserting a slightly conical metallic plug between 70 two metallic bars insulated from each other.

Having thus described the construction of the lamp, I will next proceed to explain the

mechanism which I have devised for maintaining a uniform current of any desired degree of strength through the lamp.

One of the main conductors proceeding from 5 the electric generator Y (which may be a dynamo-electric machine, a galvanic battery, or other suitable source of electricity) is attached to the binding-screw C⁴. (See Figs. 3 and 5.) The current passes thence to the binding-screw 10 C⁵ through a regulator consisting of an automatically-adjustable rheostat, hereinafter described, thence by the wire v, Figs. 1, 3, and 5, to the binding-screw C², Fig. 1, and thence by the wire v', dividing at j', j², and j³ into three 15 branches, leading respectively to the three lamps L', L², and L³, these branches again uniting upon a single wire, v², at the points j', j², and j³, their several routes being as follows: from the lamp L' to the binding-post S⁶, thence 20 through a regulator, hereinafter described, to the binding-post S⁷, thence to the wire v² at j³; from the lamp L², by the wire v³, to an automatic cut-off, hereinafter described, thence by the wire v⁹ to the wire v² at j⁴; from the lamp 25 L³ the current passes directly to the wire v², thence through the electro-magnetic or magnetizing helices M' of an automatic regulator, hereinafter described. The wire v² terminates at the binding-screw C', to which is attached 30 the return main conductor leading back to the other pole of the electrical generator.

The automatic regulator, which is interposed in the circuit leading from the source of electricity and in the main conductor, (or portion 35 thereof which is common to all the lamps in the system,) may be constructed in various ways, the general principle being that any increase in the normal strength of the current acting upon the regulator shall set in action mechanism 40 acting to diminish said current, while the reverse effect will take place when the strength of the current acting upon the regulator is diminished. One very effective arrangement for this purpose is shown in the drawings, which 45 I will now proceed to describe.

A cylinder or roller, G', Fig. 3, composed of non-conducting material, is shown as mounted upon a metallic standard, D⁸. Another cylinder or roller, G², of similar size and form, but 50 composed of metal, is mounted upon a metallic standard, D⁷. A third cylinder or roller, G⁵, of considerably greater diameter is mounted above the rollers G' and G², but in the same vertical plane, upon a standard, D². A flexible strip or 55 ribbon composed of some conducting metal having considerable specific resistance to the passage of a current—such, for example, as German silver—having one of its ends attached to the non-conducting roller G' at the point R', passes thence around the periphery of the said 60 roller, across to the metallic roller G², and around its periphery in the opposite direction, terminating at the point R². A band of cloth, paper, or other suitable insulating material, G⁴, is also 65 attached at the point R', and passes around the roller G', as shown in the drawings, beneath the metallic ribbon. This insulating-ribbon G⁴

is wound upon the large roller G⁵, the slack being taken up and the ribbon kept tight by means of the spiral spring 4 acting upon the 70 pulley G⁸ by means of the bell-crank lever G⁷ and the cord G⁶.

It being premised that one terminal of the metallic ribbon R' is connected through the axis-standard D⁶ of the roller G' with the binding-screw C⁴, while its other terminal, R², is in like manner connected through the standard D⁷ and metallic body of the roller G² with the binding-screw C⁵, it will be readily seen that the revolution of the rollers G' and G² in the 80 direction indicated by the arrows would have the effect of increasing the resistance of the circuit between C⁴ and C⁵, because the current only has to pass through such portion of the ribbon R' R² as is not in contact with the metallic roller G². Therefore the more the ribbon is wound upon the insulating-roller G' and off from the metallic roller G² the greater will be the resistance, and vice versa. A great advantage is gained by making this resistance- 85 conductor in the form of a broad and thin ribbon, as its great radiating-surface tends to prevent it from becoming unduly heated by the passage of the current. The required movement of the rollers G' and G² in one direction 90 or the other I prefer to effect by means of an independent motor. (Best seen in Figs 2 and 5.) The particular construction and arrangement of this motor are immaterial. Any known form of electromotor will serve the purpose well. 95

I have shown a well-known form of electro-motor, consisting of three straight electro-magnets, M⁵ M⁶ M⁷, fixed at an angle of one hundred and twenty degrees with each other upon a common axis, K', mounted in bearings D³ 105 D⁴, and arranged to revolve between the north poles Nh and the south poles Sh of three stationary permanent magnets. (See Fig. 5.) By means of commutators k' k² k³, of well-known construction, an electric current passing 110 through the electro-magnets is reversed at such intervals as to create alternate attraction and repulsion between the poles of the permanent and electro magnets, and thus produce a rapid rotation of the axle K'. The electric current 115 for actuating this motor may be derived from an independent source of electricity connected with the binding-screws C⁹ and C¹⁰; or it may be taken from the main current by means of a branch or derived circuit, in a manner well 120 understood.

Upon the axis K' of the electromotor is an endless screw or worm, A', which works into the teeth of a wheel, W, (see Fig. 2,) upon the axle K² of which is a pinion, P². (See Figs. 5 125 and 6.) A universal joint, V', Fig. 5, in the axle permits the pinion P² to be moved horizontally in one direction or the other, so as to engage with one or the other of the toothed wheels F' F², which are mounted upon the respective axles K³ K⁴ of the rollers G' G². 130

As the motor hereinbefore described, when in action, always revolves in one direction, carrying with it the axle K² and pinion P²,

it is obvious that the system of rollers G' , G^2 , and G^3 will be caused to turn in one direction or the other as the pinion P^2 is engaged with one or the other of the toothed wheels F' F^2 .

5 I will now describe the mechanism whereby the pinion P^2 is shifted and the manner in which it is automatically operated by the increase or decrease of the normal current traversing the system.

10 Referring to Fig. 4, M' represents one of a pair of electro-magnetic or magnetizing helices, which are placed in one of the branch circuits uniting the poles of the generator, as shown in Fig. 1.

15 Instead of the arrangement of soft-iron cores and armature ordinarily employed in electro-magnets, I generally prefer to make use of movable cores in connection with the magnetizing-helices M' , which cores tend to be drawn 20 into said helices by the action of the electric current. The movable cores or armatures, as the case may be, are attached to one end of a horizontal beam or lever, B , pivoted at or near its center upon a standard, F , the attractive force 25 of the helices being opposed by the constant force of an adjustable antagonistic spring, 2. The lever B is capable of a slight oscillatory motion upon its axis in a vertical plane, which oscillation is limited in each direction by adjustable screw stops inserted in standards f and b , of insulating material, and with its connections, hereinafter described, forms a circuit-changer which is actuated by the helices M' .

30 One pole of a battery or other generator of electricity is connected with the standard F by means of the wire w' , which terminates in a binding screw, C^3 . The adjustable contact-screw f is connected by wire w^2 with binding-post C^7 , and thence by wire w^4 (see Fig. 5) with electro-magnet M^3 . Similarly, the contact-screw b is connected by wire w^3 , binding-post C^6 , and wire w^5 (see Fig. 5) with electro-magnet M^4 . The electro-magnets M^3 and M^4 are 40 connected by wires w^7 and w^6 , respectively, with a common binding-post, C^8 , to which the remaining pole of the battery or other generator above mentioned is connected. I here remark 45 that the regulator may be supplied with electricity by means of a branch from the main circuit which supplies the lamps, if preferred, in the same manner as the motor hereinbefore referred to. In most cases it will be found

50 preferable to include the motor in the return-circuit, which is common to the electro-magnets M^3 and M^4 , which may be effected by connecting the binding-screws C^8 and C^9 by means of a wire and the binding-screws C^3 and C^9 with a source of electricity, in which case the 55 motor will only be set in action when the pinion P^2 is shifted in one direction or the other by the action of the regulator.

60 It will be understood from the explanation which has been given that as the lever B is deflected from its normal position of equilibrium under the greater or less attraction exerted by the regulating-helices M' the electric

current will be directed through one or the other of the electro-magnets M^3 M^4 , as the case may be. By reference to Fig. 5 it will readily be understood that the electro-magnet M^3 , when set in action, will attract its armature, and thus throw the pinion P^2 into gear with the wheel F' ; and in like manner the magnet M^4 will throw the pinion P^2 into gear with the wheel F^2 . Thus, if the current through the regulating-magnet M' tends to become too strong, the lever B makes contact with the point f , throwing the magnet M^3 into action, which shifts the pinion P^2 in such a manner as 80 to cause the motor to interpose an increased resistance in the circuit, in the manner hereinbefore explained, and thus reduce the strength of the current passing through the magnet M' and the lamps to its normal limit. A decrease 85 in the normal strength of current acts in the same manner upon the magnet M^4 , and by reversing the operation above described withdraws a certain amount of resistance from the circuit. By this means the current traversing 90 the lamps may be automatically kept at all times at a practically uniform strength, which may be adjusted at pleasure by altering the tension of the spring 2 and the position of the contact-stops f and b .

95 I sometimes prefer to arrange the lever B so as to work against movable levers l^c and l^b , Fig. 4, which are hinged or pivoted to upright standards b' , E' , and E^2 , and are normally kept in contact with adjustable stops by means of springs 1 and 3. These are so adjusted that the beam or lever B breaks one contact at the same instant that it makes the other. Thus the interval between the alternate action of the magnets M^3 and M^4 may be lessened. It 100 will be understood that by means of the regulating devices above described the danger of fusing the metallic strip which forms the light-producing portion of the lamp is avoided.

105 In putting a lamp in action by closing its appropriate switch the resistance of the light-producing portion of the lamp constantly increases as its temperature becomes higher, and this increase in the resistance of the lamp tends to weaken the current, which instantly affects 110 the automatic regulator in the manner hereinbefore described, and causes it to diminish the resistance of the rheostat, so that the resistance of the latter decreases as that of the lamp 115 increases, and vice versa.

120 In addition to the general regulator above described, it is frequently advisable to provide each individual lamp with a special device for controlling the current passing through it without reference to the others. I have shown an 125 automatic cut-off applied to one of the lamps, L^2 , for this purpose. (See Figs. 1 and 7.) This device consists of an electro-magnet, M^2 , (best seen in Fig. 7,) having its armature attached to a pivoted lever, v^6 , which is provided with 130 a retracting-spring, v^9 , arranged in the ordinary manner. A flat spring, v^7 , is mounted upon an insulating support upon the armature-lever v^6 , and whenever the lever is drawn down

by the action of the electro-magnet the under side of the free end of the spring v^7 touches the post v^{10} and lifts the spring from the contact-point v^{11} on the end of the lever v^6 .

5 By tracing the circuit of the lamp L^2 in Fig. 1 it will be seen that it passes from the lamp by the wire v^3 to the coils of the electro-magnet M^2 , thence by wire v^5 to the base of the apparatus and the lever v^6 , which is electrically 10 a part of it, and thence through the contact-point v^{11} , spring v^7 , and wire v^9 to the junction of the common return-wire at j^4 . Thus it will be seen that any increase in the normal strength 15 of the current traversing the lamp L^2 and the electro-magnet M^2 will cause the lever v^6 to be slightly drawn down. This movement will cause the electro-magnet to break its own circuit between v^6 and v^7 , which will, however, be instantly restored as soon as the magnetism of 20 the magnet M^2 is in any degree weakened. By adjusting the contact-screw v^{11} the normal strength of current which it is desired to maintain can be regulated with great precision.

The above-described arrangement may be 25 modified by connecting a wire, v^{12} , from the post v^{10} (which must be insulated from its base) to a point between the lamp L^2 and the peg-switch S^4 , (see Fig. 1,) in which case the current through the lamp will be diminished, when 30 too strong, by the last-named connection acting as a shunt and diverting a portion of the current to the branch passing around and outside of the lamp L^2 and magnet M^2 .

Another form of cut-off or regulator (not 35 automatic in its action) is shown in Figs. 1 and 8 in connection with the lamp L' . The branch of this lamp is separated at a point between the binding-posts S^6 and S^7 , to which posts are attached two parallel wires, $u^1 u^2$, of 40 platinum, iridium, or other suitable alloy of high specific resistance, upon which a movable metal block, R' , is fitted to slide, and which forms an electrical connection between the said wires, thus completing the circuit. By 45 sliding the block R' to a greater distance from the binding-posts S^6 and S^7 the current is forced to pass through a greater length of the resisting-wires $u^1 u^2$, and its force may in this manner be decreased at pleasure or increased by 50 moving the block R' in the opposite direction.

I do not limit myself to the specific construction and organization of apparatus shown, as these details may be greatly varied without departing from the principles of my invention.

55 I do not herein claim the details of the apparatus for controlling the operations of the rheostat, the location thereof in a branch or derived circuit, or the form or construction of 60 the lamp; nor do I claim preventing the fusion or illuminating conductors by interrupting or shunting the currents, or the method of connecting lamps in multiple arc or multiple series, as these constitute the subjects-matter of 65 other pending divisions of this application.

I claim as of my own invention—

1. The combination, substantially as herein-

before set forth, of a generator of electricity, a circuit of conductors uniting the poles of 70 said generator, one or more electric lamps included in said circuit, a rheostat consisting of flat metallic ribbon which is included in said circuit, two rollers, one composed of conducting and the other of non-conducting material, arranged substantially as described, for winding 75 said ribbon back and forth from one to the other of said rollers, and a band of non-conducting material interposed between the several convolutions of the ribbon upon the non-conducting roller.

80 2. The combination, substantially as herein-before set forth, of a generator of electricity, a circuit of conductors uniting the poles of 85 said generator, one or more electric lamps included in said circuit, a rheostat consisting of a ribbon of conducting material, which is capable of adjustment by being wound from a conducting to a non-conducting roller, and the reverse, and an additional actuating-roller 90 for winding said ribbon in one direction or the other.

3. The combination, substantially as herein-before set forth, of a generator of electricity, a circuit of conductors uniting the poles of 95 said generator, one or more electric lamps included in said circuit, a rheostat consisting of a ribbon of conducting material included in said circuit, which is capable of adjustment by being wound from a conducting to a non-conducting roller, and the reverse, and mechanism 100 for winding said ribbon in one direction or the other, consisting of a roller, a driving-shaft, a shifting-pinion, and two toothed wheels which are driven in opposite directions by the same motor.

105 4. The combination, substantially as herein-before set forth, of a generator of electricity, a circuit of conductors uniting the poles of 110 said generator, one or more electric lamps included in said circuit, a rheostat included in said circuit, consisting of a ribbon of conducting material, the resistance of which is capable of adjustment by winding the ribbon from a conducting to a non-conducting roller, and the reverse, a motor which effects such adjustment by moving in one direction, and a shifting or reversing device controlled by one or more independent electro-magnets, the respective action of which is determined by a 115 regulator actuated by the current which passes through the rheostat.

5. The combination, substantially as herein-before set forth, of a generator of electricity, a circuit of conductors uniting the poles of 120 said generator, one or more electric lamps included in said circuit, and a rheostat or artificial resistance (included in said circuit) consisting of a thin flat metallic ribbon having a 125 large radiating-surface.

MOSES G. FARMER.
